UNITED STATES PATENT OFFICE.

JOHN W. KRISCH, OF KANSAS CITY, MISSOURI.

DESIGN FOR A FINGER RING.

Application filed November 21, 1927. Serial No. 24,222. Term of patent 3½ years.

To all whom it may concern:

Be it known that I, JOHN W. KRISCH, a citizen of the United States, residing at Kansas City, in the county of Jackson and State of Missouri, have invented a new, original, and ornamental Design for a Finger Ring, of which the following is a complete specification, reference being had to the accompanying drawing, forming a part thereof.

Figure 1, is a plan view of a finger ring, embodying this design.

Fig. 2, is an edge elevation of the same.

Fig. 3, is a side elevation of the same.

I claim:

The ornamental design for a finger ring as shown.

JOHN W. KRISCH.
